UNITED STATES PATENT OFFICE.

ALLISTER S. MITCHELL, OF DETROIT, MICHIGAN, ASSIGNOR TO CALIFORNIA COTTON MILLS COMPANY, OF OAKLAND, CALIFORNIA, A CORPORATION OF CALIFORNIA.

BATT-INSERTING TOOL.

Original application filed February 28, 1927, Serial No. 171,462. Divided and this application filed February 10, 1928. Serial No. 253,460.

This invention has to do with a tubular insertion-tool adapted to the purpose of stuffing pipes or pleats of cushioned upholstery and the like and the primary object of the invention is to provide a tool for this purpose which is adjustable in such manner as to adapt it for use in filling or stuffing pipes or pleats of different dimensions in cross section, thus eliminating the necessity of providing a separate tool of fixed and definite cross sectional dimensions to meet the requirement of the cross sectional dimensions of the specific pleat or flue to be filled.

This application is a division of my application, Serial Number 171,462, filed February 28, 1927.

The improved tool is suitable for use in practicing the Mitchell process of stuffing or filling upholstery which is described in my Reissue Patent No. 16,283, granted March 9, 1926. In the process described in said patent, the advance end of a continuous strip of batting or filling drawn from a suitable supply is confined within a tubular insertion-tool. The tool is inserted in a pleat or pipe, the advanced end of the strip, then held while the tool is withdrawn from the tube or pleat, thus reloading the tool; the strip is then severed at the advance end of the tool by giving the tool a quick movement laterally of the pleat or pipe, severing the strip of batting or filling at the end of the pleat or pipe.

The process just described is now practically universally employed for stuffing or filling pleats or pipes in upholstery. In stuffing or filling pleats or pipes of this nature, it has been the custom to provide an insertion-tool to fill a pleat of a given cross sectional area, but such tools have never heretofore been so constructed as to make it possible to vary the normal cross sectional area of the tool so that the tools could be used universally, thus accommodating the tool to pipes or pleats of different cross sectional dimensions. As many large trimming shops are called upon to stuff or fill pleats or pipes of varying cross sectional dimensions, they are required to provide a separate tool of specific diameter to fit the cross sectional dimensional diameter of the specific cross sec-

tional dimensions of the pipes or tubes requiring filling.

In accordance with the present invention, the tool is made of adjustable cross sectional area, thus providing a tool that can be quickly and readily adjusted to render it suitable in cross sectional dimensions for stuffing or filling a number of pipes or tubes having different cross sectional dimensions. It will be readily seen that by the provision of this adjustable tool that the heretofore necessity of providing a multiplicity of such tools to meet the requirements of the filling or stuffing pipes or tubes of different cross sectional dimensions is eliminated.

The invention is illustrated in its preferred embodiment in the accompanying drawings, in which:

Fig. 1 is a plan view of the improved insertion-tool, the tool being shown adjusted to its largest capacity.

Fig. 2 is a transverse section of an enlarged scale taken at line 2—2 of Fig. 1.

Fig. 3 is a broken section taken on a line 3—3 of Fig. 4.

Fig. 4 is an end view partially in section.

Fig. 5 is a broken plan view.

For a more comprehensive and clearer understanding of the invention, reference is made to the reference characters shown on the drawing in which like reference characters indicate like parts.

The main body portion of the tool comprises two concavo-convex members A and B in substantially parallel relation, which members may be struck from strips of relatively thin metal. Members A and B are flared outwardly adjacent their lower ends as at 10 and 11, thus forming a flared or truncated cone portion at the base of the tool. The flared portions 10 and 11 have formed at their base channels 12 for the reception therein of U-shaped members 13 which encircle the members A and B and which may be rigidly secured within the channel 12 in any desired manner, as for instance, by soldering as at 14.

The U-shaped members 13 are provided at their inner ends with ears 15 and 16. Ears 15 and 16 have apertures therethrough for the free passage of screw-threaded bolts

17 on opposite sides of the tool which are provided with nuts 18, which bear against the faces of ears 16 and are for the purpose of drawing members A and B toward each other at their base and rocking member A on fulcrum 23^a of member B against the tension of spring 19, thus tending to move members A and B away from each other at their advance ends and increase the diameter of the tool. At a short distance inwardly of the base of portions 10 and 11 of the members A and B are secured ears 20 and 21. Ear 21 is internally screw-threaded for receiving in screw-threaded engagement tension screw 22 which functions as an adjustable fulcrum in seat 23^a in the inner face of ear 20 and is for the purpose of exerting pressure outwardly on the member B or away from member A, and acts also as a pivot for member A in its movement with relation to member B. Inwardly of lugs 20 and 21 and approximately at the angle formed between the flared portions 10 and 11 of the members A and B is placed a stabilizing band 23 which is of substantially U-shape, having one of its ends soldered or otherwise affixed as at 24 to one of the inwardly extending portions of member B and is then carried around member A and over-laps the other of the inwardly extending portions of B, there being a slot 25 provided in the over-lapping portion for the free movement therein of externally screw-threaded stud 26 which is affixed to member B and which is provided with butterfly nut 27 for securing band 23 and consequently member A in adjusted position with relation to member B.

The diameter of the inwardly turned portions of the member B is slightly greater than the diameter of the inwardly turned portions of the member A to permit of a telescopic relation of one of the members with relation to the other of the members. (See Fig. 2.)

At the advance end of the tool the members A and B have their flanges on one side of the tool provided with complementary recesses forming shallow notches 28 and have their flanges on the opposite side of the tool provided with complementary recesses forming deeper notches 29, the purpose of which formation will presently appear.

In the use of the implement, it is the usual practice to support the tool by means of a cord depending from a stationary support above the head of the operator, as illustrated in Fig. 7 of Reissue Patent No. 16,283. The advance end of the continuous strip of batting from any suitable source is introduced through the tubular tool; the pleated fabric to be stuffed is placed upon a table in front of the operator; and the operator, grasping the tool and collapsing it sufficiently to enable it to enter the pleat readily, inserts the

tool into the pleat, thus carrying the advance end of the wadding strip to the remote end of the pleat; the operator with the left hand then presses down upon the fabric at the remote end of the pleat, the fingers entering through the notches 29 of the tool and holding the advance end of the strip while the tool is withdrawn from the pleat by the right hand of the operator; and finally, the operator, while pressing down upon the near end of the pleat adjacent the point-end of the tool, gives the tool a quick lateral movement, causing the shallow notches 28 to sever the strip as a result of the jerking action. In the withdrawal of the tool, while the strip is held in the pleat, a fresh section of the continuous wadding-strip is drawn into the tool, so that the tool is thus reloaded. The operator repeats the operation described, and thus successive pleats are stuffed with great rapidity.

Having thus described my invention, what I claim is:

1. A pleat stuffing tool comprising a pair of complementary tube sections equipped at their base ends with adjustable spring devices tending to draw the base ends together, adjustable fulcrums between said tube sections in front of said adjustable spring connections and adjustable means for limiting the expansion of the tool.

2. A pleat stuffing tool comprising a pair of complementary substantially U-shaped cross section members, said members flaring outwardly at their base ends, means for contracting and expanding the base of the tool, a stabilizing device at approximately the smallest diameter of the flared portion and fulcrums intermediate the contracting and expanding means and the stabilizing device.

3. A pleat stuffing tool comprising a pair of complementary members in substantially parallel relation, said members forming a truncated cone for a portion of their length at the base end of the tool, means for varying the diameter of the tool at its base, stabilizing means at approximately the shortest diameter of the cone-like portion and adjustable fulcrums intermediate the varying means and the stabilizing means.

4. A stuffing tool comprising two coaxing members in substantially parallel relation assuming the form of a truncated cone for a portion of their length at the base of the tool, means for forcing the members away from toward each other at their base, adjustable stabilizing means carried by the truncated portion at approximately the shortest diameter thereof, ears carried by the respective members, one of said ears engaging an adjustable member fulcruming on the other of said ears, one of said ears being internally screw-threaded for the reception therein of a screw-threaded adjusting member, the other of said ears having a seat

formed therein for seating the end of the adjusting member.

5. A pleat stuffing tool comprising a pair of complementary coacting members of substantially U-shape in cross section and forming a truncated cone for a portion of their length at the base of the tool, resilient

members carried by and within the base of the tool, ears carried by the ends of the resilient members, and spring tensioned screw-threaded means for engaging the ears. 10

In testimony whereof I affix my signature.

ALLISTER S. MITCHELL.
